Patented Sept. 7, 1976

241,349

CHEMICAL SPRAYER

James G. Parke, San Antonio, Tex., assignor to Micro-
Gen Equipment Corp., San Antonio, Tex.

Filed Mar. 31, 1975, Ser. No. 563,669

Term of patent 14 years

Int. Cl. D23—01

U.S. Cl. D23—18

FIG. 1

FIG. 2

FIG. 3

FIG. 4

FIG. 5

FIG. 6

FIG. 7

FIG. 8

FIG. 1 is a top plan view of a chemical sprayer showing my new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a bottom plan view thereof;

FIG. 7 is a front perspective view thereof with the directional blowing portion being elevated; and

FIG. 8 is a rear perspective view thereof.

I claim:

The ornamental design for a chemical sprayer, as shown.
